FIG. 4

FIG. 5

FIG. 8

FIG. 1 is a perspective view of a bracket and mounting support for swivel shelf embodying my new design, with the shelf omitted for convenience of illustration only;

FIG. 2 is a side elevational view thereof with the mounting support broken off along its length for convenience of illustration only;

FIG. 3 is a bottom plan view thereof;

FIG. 4 is an enlarged rear elevational view thereof;

FIG. 5 is a perspective view of a modification bracket and mounting support for swivel shelf, with the shelf omitted for convenience of illustration only;

FIG. 6 is a side elevational view of the modification;

FIG. 7 is a bottom plan view of the modification; and

FIG. 8 is a rear elevational view of the modification.

The showing of a shelf in broken lines in FIGS. 2, 3, 4, 6, 7 and 8 is for illustrative purposes only.

I claim:

The ornamental design for a bracket and mounting support for swivel shelf, substantially as shown and described.
